CLAIM

The ornamental design for a shoe sole, as shown and described.

DESCRIPTION

FIG. 1 is a medial side perspective view of a shoe sole showing the new design;

FIG. 2 is a bottom view thereof;

FIG. 3 is a front view thereof;

FIG. 4 is a rear view thereof;

FIG. 5 is a medial side view thereof; and,

FIG. 6 is a lateral side view thereof.

The broken lines shown in the drawings illustrate environment or portions of the shoe sole that form no part of the claimed design.

A left-foot shoe is illustrated in FIGS. 1-6. A second embodiment of the design includes a right-foot shoe, which is a mirror image of the views of the first embodiment.
